UNITED STATES PATENT OFFICE.

JOHN J. RICHTER, OF THIEF RIVER FALLS, MINNESOTA.

PACKING-RING.

1,316,464.

Specification of Letters Patent. Patented Sept. 16, 1919.

Application filed February 12, 1916, Serial No. 77,954. Renewed December 2, 1918. Serial No. 265,052.

To all whom it may concern:

Be it known that I, JOHN J. RICHTER, a citizen of the United States, residing at Thief River Falls, in the county of Pennington and State of Minnesota, have invented a new and useful Improvement in 5 Packing-Rings, of which the following is a specification.

The object of this invention is to provide 10 improvements in packing rings for use on pistons of engines, pumps and similar machines, and particularly for pistons of internal combustion engines, wherein the ring will remain tight at all times automatically 15 under working conditions to which rings of this character are usually subject.

In the accompanying drawing forming part of this specification, Figure 1 is a view of the device, detached, illustrating in full 20 and dotted lines the appearance assumed when the ends are in interlocking position; Fig. 2 is a plan of a detail; Fig. 3 is a detail view, broken away, of the interlocking end portions of the ring, the ends being 25 slightly separated; and Fig. 4 is a similar view of a single end portion of the ring.

With piston rings now in general use, there is always more or less leakage due to 30 the rings wearing away on their outer faces, and the ends separating, thus permitting the fluid under compression to leak through.

My invention overcomes this objection by constructing the overlapping ends of the ring, so that as the ring wears away in use 35 and opens out the ends will still be held firmly in contact with each other, and thus prevent leakage.

In the drawing A is the usual body portion of a ring having ends 2 and 3 which 40 are adjacent. Each of these ends is formed with a forwardly projecting overlapping side tongue 4 and a laterally projecting shoulder 5 forming a side groove, said tongue being cut away longitudinally on its 45 under or inner edge and said shoulder and groove being formed by a portion of the end of the ring being cut away along the side of the tongue. The adjacent ends of the ring are similarly constructed, each having a side tongue and an adjacent side 50 groove, the tongue in one member entering the groove in the opposite member. The grooves and tongues in the opposite members are of sufficient depth to produce side

seating surfaces 6 for the tongues which 55 will prevent leakage of compressed liquid past the ring when the latter is in use. It will be observed that the ends of the seating surfaces are of enlarged area so that the ring can expand and contract without 60 opening and leaking.

In producing the ends as shown, a portion of the ring such as 7 is welded to the remaining portion to enable milling the ends with the overlapping joint as described. 65 By welding the ring, the ends can be made to overlap any distance desired. Also by milling the ends, the surfaces can be finished to produce an absolutely leak proof joint. Preferably the ring in normal position has sufficient opening between its ends, so that sufficient expansion of the ring is provided to produce a tight fit in the cylinder with which the ring is employed. The ring being made of resilient material permits the face of the ring wearing away to a considerable extent. As the surface of the ring wears away and expands, the overlapping surfaces 6 on its ends produce a leak 70 proof joint.

In accordance with the patent statutes, I have described the principles of operation of my invention, together with the apparatus which I now consider to represent the best embodiment thereof, but I desire to 85 have it understood that the construction shown is only illustrative, and that the invention can be carried out by other means and applied to uses other than those above set forth within the scope of the following claims.

Having described my invention, what I claim as new and desire to protect by Letters Patent is:

1. A packing ring comprising a split 95 ring, the two ends being cut away symmetrically to interlock with each other, each end comprising a tongue curved on the inner edge of its extreme end to engage a correspondingly formed groove in the opposite end of the ring, said engaging tongues and grooves being arranged in two adjacent steps to form interlocking shoulders therebetween, said shoulders being broader at the ends of the tongues and grooves than at 100 their mid-points.

2. A packing ring comprising a split ring, the two ends being cut away to form

interlocking overlapping surfaces, the transverse dimensions of each of said surfaces being less intermediate its length than at its ends.

5 3. A packing ring comprising a split ring, the two ends being cut away symmetrically to form interlocking surfaces, each of

said surfaces being curved on their inner edges in reverse curves and the transverse dimensions of each of said surfaces being ¹⁰ less intermediate its length than at its ends.

In testimony whereof, I have signed my name to this specification.

JOHN J. RICHTER.
